UNITED STATES PATENT OFFICE.

ANDREW J. McIVER, OF HOSFORD, FLORIDA.

RAILWAY-SWITCH.

1,278,961.

Specification of Letters Patent. Patented Sept. 17, 1918.

Application filed July 5, 1916. Serial No. 107,645.

To all whom it may concern:

Be it known that I, ANDREW J. McIVER, a citizen of the United States, residing at Hosford, in the county of Liberty and State 5 of Florida, have invented new and useful Improvements in Railway-Switches, of which the following is a specification.

This invention relates to improvements in the construction of railway switches.

10 An object of the invention is to construct a switch for rails in which the parts are so arranged or associated as to insure the safety of the rolling stock passing over the switch and wherein the rolling stock will be conducted upon a main line or siding regardless of the position to which the switch rails have been moved.

It is a further object of the invention to 20 arrange the connecting or bridle rods of the switch points as well as the throw rod for the switch in suitable openings or depressions formed in the ties so that a positive and accurate longitudinal movement of the bridle rods will be insured.

25 With the above and other objects in view, the improvement resides in the construction, combination and arrangement of parts set forth in the following specification and falling within the scope of the appended 30 claim.

In the drawings:

Figure 1 is a plan view with the main line open to the side line,

Fig. 2 is a similar view with the main line 35 closed,

Fig. 3 is an enlarged sectional view approximately on the line 3—3 of Fig. 2,

Fig. 4 is a sectional view approximately on the line 4—4 of Fig. 3,

40 Fig. 5 is a sectional view approximately on the line 5—5 of Fig. 2,

Fig. 6 is a longitudinal sectional view approximately on the line 6—6 of Fig. 1, and

45 Fig. 7 is a horizontal sectional view approximately on the line 7—7 of Fig. 6.

In the drawings, 1 designates the rails of the main track, 2 the rails of the siding, 3 the switch points between the siding rails and the main rails, 4 the ordinary ties which 50 support the rails and 5 the ties which are arranged to support the switch points and rails disposed adjacent to the switch points. These last named ties are hollow or are centrally provided with longitudinally extending slots or passages, the said ties also hav-

ing their upper and lower faces provided with rectangular slots 6 which terminate at suitable distances away from the ends of the ties and which, of course, communicate with the central passages in the said ties. Disposed to contact with the opposite longitudinal walls of the slot 6, but, of course, of a materially less length than that of the said slots are the connecting or bridle bars 7 for the switch points 3. The inner faces 60 of the switch points have secured thereto angle plates 8 which are also secured to the upper faces of the bridle rods 7, and these plates rest on the outer face of the ties and being of a greater width than that of the 70 bridle bars straddle the slots 6 and insure the proper position of the bridle bars in the slots. The bridle bars have secured to their under faces transverse plates 8', which contact with the inner face of the top of the 75 ties, to the opposite sides of the slots therein, to hold the bridle bars against outward vertical movement. The main bridle bar or the bar connected to the end of the points 3 is centrally formed with a depending lug 80 9, and to this lug is adjustably secured a rod 10, the said rod having its outer end flattened and provided with an elongated slot 11. One of the corners of the tie is slotted, as at 11', and passing through this 85 slot is the cranked end 12 of a switch rod 13, the said crank engaging in the slot 11 of the rod 10. The switch rod passes centrally through a switch stand 14 which has arranged thereon a throw arm for turning the 90 rod 13 to move the switch points 3 to close the main line or to open the side line.

Arranged upon the ties directly opposite the switch points 3 and outwardly of the rail 1 of the main line are guard rails 15, 95 which are of a greater height than that of the rails of the main line and siding. Disposed between the rails of the main line at the ends of the switch points 3 is a pair of guard rails 16. These guard rails are arranged inwardly of the main rails a distance slightly greater than the thickness of the rims of the wheels of the rolling stock and the ends of the guard rails 16 are beveled or inclined inwardly. Disposed between the outer faces of the guard rails 16 and the inner faces of the rails 1 are guide blocks 17. These blocks have their upper faces beveled downwardly at their ends, as indicated by the numerals 18, and the cen- 100 105 110

tral flat portions of said members are projected a distance sufficient to receive the flanges of the wheels of the rolling stock.

By reference to Fig. 3 of the drawings it will be noted that the main rails may be secured to the ties by a particular form of holding means or clamps. The holding means shown in the said Fig. 3 comprises two substantially similar members having their confronting edges, from adjacent their lower ends, cut inward and their upper edges provided with inwardly extending hooks 50. The contacting edges of these members, indicated by the numerals 51 and 52 respectively are straight, and the member 51 having its outer corner provided with a lug 53. The members 51 and 52 are designed to be passed through elongated openings 54 in the top and bottom walls of the tie, the said openings being of a greater width than the combined width of the said members 51 and 52, it being understood that the said members 51 and 52 are spread apart in the slots 54 and elevated and if desired, tilted to receive therebetween the base of the rail. Thereafter the hooked ends 50 of the members are brought to overlie the base of the rail, and the lug 53 is arranged beneath the tie 5. When this is accomplished, a wedge key 55 is passed through transverse openings 56 in the tie 5, the said wedge key contacting with the outer edge of the member 52 forces the same to contact with the member 51 and the member 51 into engagement with one of the end walls provided by the openings 54.

The guard rails 15 are arranged a distance from the main rails sufficient to permit of the trucks of the rolling stock being disposed approximately in a line with the said guard rails, it being understood that the guard rails 15 are of a greater height than the main rails so that should the train have

a tendency to jump the track at the switch such movement will be prevented by the 45 said guard rail 15. Should a train run into the switch going in the direction of the arrow *a* the flange of the wheels of the rolling stock after passing the switch rails will travel on the blocks 17 on to the track 50 rails. Should an extra heavy train get into the switch, the wrong way and break or open the switch point downwardly or cause the switch point to turn over, the block 17 will catch the wheels and keep them from becoming jammed and breaking any other part of the switch, and as a consequence they will be redirected to the main line so it will be noted that with a switch constructed as above described it will be impossible for a wheel to 60 jump the track at the switch.

Having thus described the invention, what I claim is:

In a device for the purpose set forth, in combination with rails of a main line and 65 rails of a side line, and guard rails therefor, ties upon which the rails rest, certain of said ties being hollow and having slots in the upper faces thereof, bridle bars arranged in the slots, angle plates secured to 70 the bridle bars, and bridging the slots and connected with the switch points, plates upon the under faces of the bridle bars also bridging the slots, an adjustable rod connected with one of the bridle bars, a rod 75 having a crank end loosely connected with the adjustable rod and arranged angularly with respect thereto, and a throw arm for the last mentioned rod.

In testimony whereof I affix my signature 80 in presence of two witnesses.

ANDREW J. MCIVER.
